UNITED STATES PATENT OFFICE.

ERNEST GEORGE MATTHEWSON, OF LONDON, ENGLAND.

COIN-FREED GAME.

SPECIFICATION forming part of Letters Patent No. 660,798, dated October 30, 1900.

Application filed February 15, 1900. Serial No. 5,336. (No model.)

To all whom it may concern:

Be it known that I, ERNEST GEORGE MATTHEWSON, a subject of the Queen of England, and a resident of Norwood, London, in the 5 county of Surrey, England, have invented certain new and useful Improvements in Coin-Freed Games, of which the following is a specification.

The object of my invention is to provide 10 means for playing a miniature game of cricket with a machine so constructed that it cannot be operated unless a coin, coins, or the like are inserted in the machine, and to carry my invention into effect I construct my improved 15 coin-freed cricket game as follows, reference being made to the accompanying drawings, of which—

Figure 1, Sheet 1, is a front elevation with the front of the case of the machine removed. 20 Fig. 2, Sheet 2, is a plan of the machine, taken under the field. Fig. 3, Sheet 3, is a plan, and Fig. 4, Sheet 3, an elevation, of the field; Fig. 5, Sheet 4, is a general view of the complete machine; and Figs. 6 and 7, Sheet 25 4, an elevation and a plan of bucket-lever for disposing of one coin when two are required to operate the machine.

The general arrangements of case, field, operating-handles, coin freed or operated mechanism, and means for delivering the ball upon the field and conducting it from the field to the delivery mechanism are similar to my coin freed or operated football game, for which Letters Patent were granted to me for 30 the United States, No. 619,897; but instead of the cranks A and B, attached to the spindles C and D of the operating-handles, actuating the legs of two football-players one of the handle-spindles is connected by its crank 35 A to levers F and G and connecting-rod H, arranged to actuate a bowler I, and the other handle-spindle is connected by its crank B to lever K and connecting-rod E and connecting-rod L to actuate a batsman M, and in place 40 of the goals in my football game stumps N N are fitted. The shape or contour of the field or ground plate O of the machine is varied from that of my football game, hereinbefore referred to, and is made as shown at Figs. 3 45 and 4, Sheet 3, the arrows shown upon the plan Fig. 3 indicating the direction of the various slopes. These slopes cause the ball

to run to different positions, as required by the game, and the circular holes P and P' shown are holes through which the ball may 55 be lost to the players. For instance, when the ball is delivered upon the field by the operating-handle after a coin, coins, or the like have been inserted in the machine the contour of the field causes it to roll to a position in front of the bowler I, and when by repeating the movement of the operating-handle the bowler is caused to strike the ball it is sent in the direction of the batsman M. Should the person operating the batsman fail 60 to bat the ball, it will hit the stumps and fall down through the hole in front of the stumps and be conducted by the channels Q to the delivery-bucket R, and the game is lost to the batsman. Should, however, the batsman 65 be made to strike the ball, it may go to any part of the field, and by the peculiar contour of the ground or field it will always run either back to the bowler to be played with again or to one or other of the holes through the 70 field, those at the extreme ends counting boundary hits and those in the other parts counting caught out. In either case when the ball goes through either hole it is led by the channels Q back to the delivery-bucket 75 ready to be redelivered upon the field upon the insertion of a coin, coins, or the like in a similar manner to that in my football game.

The action of the bowler I is as follows: The lower part of one leg is fixed to the field 80 or ground plate and is hinged at the knee to the thigh, which is again hinged to the body. The other leg is in one piece with the body and is continued by a lever G below the foot. This lever passes through the ground-plate 85 O and is pivoted just below it, and its extremity is connected to a lever F, attached to the crank A upon the operating-handle spindle, so that when the operating-handle is depressed the crank actuates the lever F, 90 which in turn tilts the bowler's body forward. The lever F is carried beyond the position where the lever G from the man's leg is pivoted and the action of putting the lever from the man's leg backward also depresses the extended end. To this extended end a connecting-rod H is attached, which passes up 95 the leg of the man and is connected inside his body with the bowling-arm, which is 100

hinged at the shoulder, so that the combined action by one depression of the operating-handle causes the bowler to lean forward, which brings the hand of the bowler - arm 5 nearly on a level with the ground and at the same time causes the arm to move sharply forward, which in turn strikes the ball, which rolls to a position in front of the bowler arranged for this purpose. When the bowler 10 has been caused to strike the ball, the person actuating the batsman must be ready to actuate the batsman so as to strike the ball with his bat. The action of the batsman may be similar to the bowler, or both legs 15 may be fixed to the ground, as shown in the drawings, and the action of the crank B, attached to the handle-spindle, causes connecting-rod E and the lever K to draw down the connecting-rod L, which is carried up through 20 one of the legs of the batsman and actuates the upper part of the body, which is pivoted in the center and carries with it in one piece

the arms and bat. Models of fielders may be placed near the holes P', if desired.

Having now particularly described and ascertained the nature of my said invention and in what manner the same is to be performed, I declare that what I claim is—

In combination with a board having an undulating surface for causing a ball to roll in various directions, a figure of a bowler having a swinging arm, means for operating said arm to cause it to bowl a ball, a wicket at the opposite end of said field, a batsman in advance of said wicket having a swinging bat 35 and means for causing said bat to swing, substantially as described.

In witness whereof I have hereunto set my hand in presence of two witnesses.

ERNEST GEORGE MATTHEWSON.
